(57) CLAIM

The ornamental design for a vehicle ottoman, as shown and described.

DESCRIPTION

FIG. 1 is a front left perspective view of a vehicle ottoman, showing our new design in use conditions, the broken lines showing the vehicle interior that form no part of the claimed design;

FIG. 2 is a rear left perspective view thereof;

FIG. 3 is a front elevation view of the vehicle ottoman alone;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown in FIGS. 1 and 2 of the vehicle interior are included for the purpose of illustrating environmental structure only and form no part of the claimed design.
